UNITED STATES PATENT OFFICE.

PAUL A. JAENICKE AND MIKE LITKE, OF ST. LOUIS, MISSOURI, ASSIGNEES TO RICE-STIX DRY GOODS COMPANY, OF ST. LOUIS, MISSOURI, A CORPORATION OF MISSOURI.

WARDROBE TRUNK.

Application filed September 19, 1923. Serial No. 663,550.

To all whom it may concern:

Be it known that we, PAUL A. JAENICKE, and MIKE LITKE, citizens of the United States, and residents of the city of St. Louis and State of Missouri, have invented a new and useful Improvement in Wardrobe Trunks, of which the following is a specification.

This invention relates principally to ironing board attachments for wardrobe trunks comprising two sections that are hinged together, one section being provided with a tier of drawers and the other section being provided with a wardrobe compartment, within which clothes are suspended on suitable hangers, and a removable shoe box.

One of the principal objects of the present invention is to provide the wardrobe trunk with a simple and efficient ironing board attachment of rigid construction and compact design which can be readily assembled in position for ironing. Another object of the invention is to provide the trunk with means which is available in the closed position of the trunk as a lock for the tier of drawers thereof and which is available in the open position of the trunk as a support for the ironing board. Another object is to provide the trunk with a receptacle which cannot be displaced in the closed position of the trunk but which may be readily removed in the open position thereof.

The invention consists principally in a single means adapted to serve as a support for an ironing board attachment for a wardrobe trunk or as a lock for a tier of drawers thereof. The invention further consists in means for removably securing a shoe box in position within the trunk; and it also consists in the parts and in the arrangements and combinations of parts hereinafter described and claimed.

In the accompanying drawings, which form part of this specification and wherein like symbols refer to like parts wherever they occur,

Fig. 1 is a side view of a wardrobe trunk embodying my invention, the trunk being shown open;

Fig. 2 is a view similar to Fig. 1 showing the ironing board attachment set up for use;

Fig. 3 is a vertical longitudinal section through the ironing board;

Fig. 4 is a vertical section through the

lower end portion of the wardrobe section 55 showing the manner of mounting the shoe box;

Fig. 5 is a fragmentary front elevation of the lower left-hand corner of the trunk section, and shoe box, the trunk section being 60 shown in section to disclose the hinge for the shoe box;

Fig. 6 is a horizontal section on the line 6—6 in Fig. 3 looking toward the under side 65 of the ironing board;

Fig. 7 is a fragmentary vertical section through the uppermost brace of the trunk section containing the tier of drawers; and

Fig. 8 is a horizontal section through the locking bar on the line 8—8 in Fig. 1, the 70 section being shown adjacent to the lowermost cross-brace to disclose the shape of the notch therein.

The wardrobe trunk shown in the accompanying drawings comprises two trunk sections 1 and 2 that are hinged together. The section 1 is provided with a hinged cover section 3 which, when the two trunk sections 1 and 2 are closed, is held from any opening movement. The trunk section 1 is provided at its top with a pair of spaced parallel supporting rods 4 that are secured to the sides of the trunk sections by means of brackets 5. These rods serve as supports for clothes hangers 6 and 7 of any desired size or shape. The opposite trunk section 2 is provided with a tier of drawers 8.

The trunk section 1 is also provided with an ironing board attachment comprising an ironing board 10 provided at one end with a cross-bar 11 which projects on opposite sides of said board. The projecting end portions of the cross-bar 11 of the ironing board 10 are formed along their inner edges with semi-circular notches 12 adapted to straddle the supporting rods 4 for the clothes hangers 6 and 7, whereby said board, when not in use, is adapted to be suspended from the spaced rods 4 which support the clothes hangers 6 and 7.

The uppermost drawer 8^a of the tier or drawers 8 located in the trunk section 2 is secured in position by a lock 8^b adapted to be opened by means of a key; and the remaining drawers of said tier are secured in position by means of a bar 13. When the ironing board attachment is not in use, this bar is adapted to be placed in an upright

position across the front ends of the drawers located below the top drawer 8^a and thus serve as a lock for said drawers. The bar 13 has its upper end portion bent inwardly and 5 thence downwardly, forming a hook portion 13^a. The bar 13 is provided with a suitable lifting knob 13^b; and it has oppositely disposed notches formed in its side edges adjacent to its lower end, forming a narrow neck 10 portion 13^c. The inwardly extending portion of the hook 13^a of the bar 13 is adapted to rest in a depressed portion 14^a of a brace member 14 located between the top drawer 8^a and the series of drawers located there- 15 below; and the downwardly extending end of the hook 13^a of said locking bar 13 is adapted to enter within an elongated slot 14^b formed in the depressed middle portion 14^a of said brace member 14. The lower end 20 portion of the bar 13 is held from outward movement with respect to the drawers by means of a retaining member 15 which is secured to the lowermost brace or tie member 16 for the trunk section 2. This brace is located 25 between the lowermost drawer of the tier of drawers 8 and the next adjacent drawer thereof. The retaining member 15 for the lower end portion of the locking bar 13 extends outwardly beyond the drawers 30 of the trunk section 2 and has a T-shaped notch 15^a extending vertically therethrough whose wider portion is adapted to slidably receive the locking bar 13. The narrow portion 35 of the T-shaped notch 15^a is located forward of its wider portion, and forms a narrow throat adapted to receive the narrow neck portion 13^c of the bar 13.

When it is desired to lock the drawers located below the top drawer 8^a, said top 40 drawer is removed from the trunk section. The narrow neck portion 13^c in the lower end portion of the bar 13 is then entered within the narrow throat portion of the T-shaped notch in the retaining member 15 45 and pushed back into the wider portion of the notch, thereby permitting the body portion of the bar to slide down in said notch, in which position said bar is held against outward movement by the narrow neck portion 50 of said notch. The hook 13^a at the upper end of the bar 13 is then entered within the slot 14^b in the top brace 14, thereby holding the upper end of the bar against outward movement. The top drawer 8^a is 55 then replaced and secured by means of the lock 8^b, thereby preventing the upward sliding movement required to release the upper and lower ends of the bar 13.

When it is desired to use the ironing 60 board attachment, the board 10 is removed from the supporting rods 4 and the ends of the cross-bar 11 thereof entered within oppositely disposed supporting brackets 20 formed in the opposite sides of the trunk section 1 near the front edge thereof. These

brackets are provided at their tops with outwardly bent flanges having elongated slots 21 formed therein that are disposed parallel with the sides of the trunk sections. The ends of the cross-bar of the ironing board 70 are formed with downwardly bent portions 22 adapted to be entered within the slots 21 in the supporting bracket 20. The downwardly bent portions of said cross-bar are notched at their rear ends forming shoulders 75 23 adapted to engage the adjacent under surface of the supporting brackets 20. The downwardly bent ends 22 of the cross-arm of the ironing board are inserted into the slots 21 in the supporting brackets 20 at an upward inclination and then swung down into a horizontal position, in which position the shoulders 23 in the depending ends of the cross-arm of the ironing board bear against the lower surface of the supporting brackets 80 85 therefor and thus prevent upward movement of the inner end of the ironing board.

The outer end of the ironing board is supported by means of the locking bar 13 for the drawers in the trunk section 2. To remove the locking bar from its position in front of the tier of drawers, the uppermost drawer is unlocked and removed. The locking bar 13 is then lifted by means of the knob 13^b a distance sufficient to disengage its upper end from the slot 14^b in the top brace 14 of the trunk section, thus releasing the upper end of said bar. This lifting of the bar is continued until the narrow neck portion 13^c of the bar is brought opposite to the narrow throat portion of the retaining member 15 on the lowermost brace 16 for the trunk section, thereby permitting the bar to be disengaged from said member. The bar is then removed from the trunk section 2 and placed in an upright position beneath the outer end portion of the ironing board 10 with its hooked upper end entered within a slot in a channel-shaped bracket 25 that is rigidly secured to the lower surface of the ironing board. The bar is corrugated longitudinally to resist bending and when secured in position below the forward end of the ironing board forms a rigid support therefor.

The lower end portion of the trunk section is provided with a removable shoe-box 30. The shoe-box is provided at its sides near its lower front corner with angle-shaped brackets 31. One flange of each bracket is secured to the side of the shoe-box and the other flange projects outwardly from the side of said box and is adapted to cooperate with a vertical slot 32^a formed in the vertical flange of a corner bracket 32 secured in each of the lower corners of the trunk sections. The slot 32^a in each corner bracket is formed in an inwardly offset portion of the vertical flange thereof and is widened at its bottom a distance correspond- 120 125 130

ing to the width of the engaging portion of the shoe-box bracket 31, whereby said box or receptacle may be swung outwardly and downwardly and removed from the trunk section by lifting the engaging ends of said receptacle brackets out of engagement with the corner brackets of the trunk section. The advantage of this arrangement is that it holds the receptacle against displacement when the trunk is closed and permits the ready removal of the receptacle when the trunk is opened.

The hereinbefore described arrangement admits of considerable modification without departing from the invention; therefore we do not wish to be limited to the precise arrangement shown and described.

What we claim is:

1. The combination with a wardrobe trunk comprising hinged sections, of an ironing board attachment therefor comprising brackets mounted on the opposite sides of one section and provided with outstanding flanges having elongated slots therein, a board having a cross member adjacent to its inner end, and a detachable supporting member for the outer end portion of said board, said cross member having angularly bent end portions adapted to enter the slots in said brackets, said angularly bent end portions of said cross member having shouldered portions adapted to bear against the under surface of said brackets, whereby upward movement of the inner end of the board with respect to said brackets is prevented in the horizontal position of said board.

2. The combination with a wardrobe trunk comprising hinged sections, of an ironing board attachment therefor comprising slotted brackets mounted on the opposite sides of one section, a board having a cross-member adjacent to its inner end adapted to rest on said brackets, and a supporting member removably engaging the outermost position of said board, said cross arm having angularly bent end portions adapted to be entered within the slots in said brackets, said angularly bent portions of said cross arm having shouldered portions adapted to engage the under sides of said brackets for preventing upward movement of said board in the horizontal position thereof.

3. The combination with a wardrobe trunk comprising a section containing a tier of drawers of a lock for the top drawer of said tier, a locking member removably secured to said section in front of the remaining drawers of said tier, and means permitting the removal of said locking mem-

ber only upon withdrawal of said top drawer.

4. The combination with a wardrobe trunk comprising a wardrobe section, a removable receptacle therefor, means for pivotally securing said receptacle in said section for outward swinging movement only, said means comprising horizontal trunnions of wide flat section projecting from the opposite sides of said receptacle, and brackets secured to the sides of said section and having their lower portions offset inwardly and provided with vertical slots adapted to receive said trunnions, the lower portions of said slots being of a width corresponding substantially to the width of said trunnions, and the upper portions of said slots being of a width corresponding substantially to the thickness of said trunnions.

5. A wardrobe trunk comprising a section having a tier of drawers, cross-members located between the top and bottom drawers of said tier and the drawers adjacent thereto, a lock for the top drawer of said tier and a locking member for the remaining drawers of said tier, said locking member being disposed in an upright position in front of the drawers located below said top drawer, the upper end of said locking member being hooked over the uppermost cross-member of said trunk section and being slidably engaged with the lower cross-member of said section.

6. A wardrobe trunk comprising a section having a tier of drawers, cross-braces located between the top and bottom drawers of said tier and the drawers adjacent thereto, a lock for the top drawer of said tier and a locking bar for the remaining drawers thereof, said locking bar being disposed in an upright position in front of the drawers located below said top drawer, the upper end of said locking bar being hooked over the uppermost cross-brace of said trunk section and being slidably engaged with a notch formed in the front edge of the lowermost cross-brace of said section, said notch being of greater width at the rear than at the front, said locking bar having a sliding fit in the wide portion of said notch and having a narrow throat portion formed in its lower end portion corresponding substantially to the width of the narrow portion of said notch.

Signed at St. Louis, Missouri, this 15th day of September, 1923.

PAUL A. JAENICKE.
MIKE LITKE.
